PORTRABLE LAMP

Filed Sept. 15, 1927

UNITED STATES PATENT OFFICE.

ANDREW J. CARMICHAEL AND ORESTO BALZANO, OF NEW HAVEN, CONNECTICUT,
ASSIGNORS TO THE GREIST MANUFACTURING COMPANY, OF NEW HAVEN, CON-
NECTICUT, A CORPORATION OF CONNECTICUT.

PORTABLE LAMP.

Application filed September 15, 1927. Serial No. 219,636.

The invention relates to portable desk lights, and more particularly to certain improvements in the construction of the lamp base for use with such lamps.

5 An important feature of the invention is comprised in a combination of parts embodying a hollow base, a tubular or other form of hollow standard connected with base, and a central tie rod of U-shape which is attached 10 to the base at its lower end through the instrumentality of a screw and clamping nut at one end, the other end of the U-shaped tie rod being equipped with laterally extending lugs 15 minal portions to receive a pivoting member for adjustably supporting the lamp.

The foregoing, and other important features of the invention including details of construction and combinations of parts, will 20 be better understood from the following detailed description in connection with the accompanying drawings.

In the drawings,

25 Figure 1 shows a lamp in side elevation, embodying the present invention;

Figure 2 is an enlarged, sectional view of the base, standard, and lower portion of the lamp;

30 Figure 3 is a plan view of the upper washer, and

Figure 4 is a similar view of the lower washer.

The lamp base proper, 4, is preferably made of sheet metal, hollow, and at its lower 35 extremity has an inturned edge 5 which is seated in a recess 6 of a metal base 7. The base 7 is preferably made of solid metal, and is of sufficient weight to stabilize the lamp, and maintain it securely upon a flat topped 40 table, or other surface.

The base 7 is provided at its center with a thickened portion 8 having therethrough a 45 perforation 9, which is shown as receiving a screw 12. The upper end of the screw is herein shown as being riveted at 14 through an aperture at the lower, horizontal portion of a U-shaped tie rod 16. This tie rod may be made of sheet metal, of relatively light weight.

50 The base 4 tapers upwardly to a relatively diminished, circular top portion 17, which is surmounted by a washer 20, having a down-turned edge 21, and supported upon the

washer is the tubular lamp stem 22, having an open annular cap 24 at its upper end, and a second washer 26, fitting over said cap. The washer 20 is provided with oppositely arranged guiding slits 30—30 which are slipped over the U-shaped tie rod 16, and held against turning relatively thereto. The downwardly bent flange 21 of the washer fits tightly upon an upper annular portion of the base 4, thereby stiffening and strengthening the top of the base at that point where the U-shape tie rod 16 passes through the base and washer 20, 65 and the slits 30—30 receive the side members of the tie rod. These features of the washer are quite important as strengthening and centering devices for the tie rod, as the side members of the rod are held rigidly in fixed 70 positions by the slits and prevented from twisting or bending, whereby the tie rod is stiffened and supported and greatly increased strength given to the entire lamp standard thereby. 75

Near the upper end of the arms of the U-shaped tie rod are lugs 28, which are preferably bent out from the metal of the rod, as shown, and act as abutments bearing against the upper face of the washer 26. The upper 80 extremities 16^a of the rod are provided with alined perforations to receive a hollow pivot stud 31 which connects the ends of the rod with the lamp socket receiving member 35. A screw 33 is threaded to the interior of the 85 pivot stud 31, and with said stud acts to connect the ends of the tie rod pivotally to the lamp.

The tie rod may be clamped to the base by the screw 12, which passes centrally through the base 7 and is shown as clamped to said base by a nut 12^a. When the several parts are assembled as shown in the drawings, the U-shaped tie rod passes centrally through the washer 26, hollow stem 22, washer 20, and upper portion of the lamp base, and upon tightening the nut 12^a the several parts are drawn together, and clamped to each other in such manner as to form a rigid structure. Any equivalent clamping means may be used for 100 the screw 12 and nut 12^a.

The elements constituting the base and standard of the lamp as above described are simple in construction, easy to assemble and disassemble, and economical to manufacture. 105 When assembled, the construction is durable

and attractive in appearance, and if any of the parts become broken or misplaced they may be easily substituted, or replaced, without necessitating the employment of skilled labor.

Having thus described our invention, we claim:

1. In a device of the character described, the combination of a hollow conical base, an annular weighted portion supporting the base and having a central perforation, an apertured washer upon said base, a hollow stem supported upon the washer, a sheet metal U-shaped tie rod extending through said base, washer and stem and having interlocking engagement with said washer, said rod being provided above the stem with lateral abutments, a washer interposed between the upper end of the hollow stem and said abutments, and screw clamping means for securing the lower portion of the tie rod to the weight arranged to draw the several parts together.
2. In a device of the class described, the combination of an annular weight member having a central perforation, a hollow base of conical form supported by said member, a washer having spaced slits and a central opening arranged to rest upon the top of said base, a hollow stem supported upon said washer, a second washer arranged over the opposite end of said stem and having a rectangular opening therethrough, a U-shaped sheet metal tie rod extending through said base, the slits in said first named washer, said stem and said second washer, the tie rod having oppositely projecting lugs resting upon the outer face of the second washer, a screw and clamping nut at one end of said rod for drawing the several parts together, and means at the opposite end of said rod for pivotal connection to a lamp.
3. In a device of the character described, the combination of a hollow base containing a weighted member, a washer having a downturned flange fitting over the contracted top of said base, a hollow stem supported upon the washer, a U-shaped tie rod extending through said base and stem and rigidly held by said washer against lateral distortion, and means comprising a second washer at the upper end of the hollow stem through which washer said U-shaped rod passes, said rod

having means at its upper portion for attachment to a lamp.

4. In a device of the character described, the combination of a hollow base having a contracted upper extremity, with an opening therethrough, a washer fitting over said extremity, and provided with spaced slits, a U-shaped tie rod having its lower end anchored in said base, and its side members passing through the slits in said washer, whereby the tie rod is rigidly retained in alinement with the hollow stem, a hollow stem supported upon said washer and surrounding said tie rod, a second washer at the upper end of said stem provided with an aperture for receiving said tie rod, and means for connecting a lamp with said tie rod.

5. In a device of the character described, the combination of a hollow conical base, an annular weighted portion supporting the base, and having a central perforation, a washer above the base having spaced slits therein, a hollow stem supported upon the washer, a sheet metal U-shaped tie rod extending through said base, the slits in said washer, and the stem, and provided above the stem with lateral abutments, a washer interposed between the upper end of the stem and said abutments, and clamping means for securing the lower portion of the tie rod to the weight arranged to draw the several parts together.

6. In a device of the class described, the combination of a weight member having a central perforation, a hollow base of conical form supported by said member, a washer having spaced slits arranged to rest upon the top of said base, a hollow stem supported upon said washer, a second washer arranged over the opposite end of said stem and having an opening therethrough, a U-shaped tie rod extending through said base, the slits in said first named washer, said stem, and said second washer, the tie rod having laterally projecting lugs, engaging said second washer, and means for tightly securing the several parts together.

In testimony whereof we have hereunto set our hands this 19th day of August A. D. 1927.

ANDREW J. CARMICHAEL.
ORESTO BALZANO.
